UNITED STATES PATENT OFFICE.

DONOVAN FOSTER AND LEROY L. MIDDELKAMP, OF SEATTLE, WASHINGTON.

SEARCHLIGHT.

Application filed February 20, 1920. Serial No. 360,213.

To all whom it may concern:

Be it known that we, DONOVAN FOSTER and LEROY L. MIDDELKAMP, citizens of the United States, residing at Seattle, in the 5 county of King and State of Washington, have invented certain new and useful Improvements in Searchlights, of which the following is a specification.

This invention relates to search-lights and 10 more especially to apparatus of this character which are employed upon pilot-houses of marine vessels to facilitate making landings at docks, etc.

The object of our invention is the provision 15 of a search-light provided with devices to enable the search-light to produce selectively a concentrated beam or a diverging beam through the instrumentality of means which are manually actuated as, for example, from the interior of a pilot house.

The invention consists in the novel construction and combination of devices for regulating the position of the source of light with respect to the lens of a search- 25 light.

In the accompanying drawing,

Figure 1 is a longitudinal vertical elevation of a search-light embodying the present invention shown applied.

30 Fig. 2 is a transverse vertical sectional view through 2—2 of Fig. 1. Fig. 3 is a horizontal sectional view through the lamp casing shown in the preceding views, the light bulb being omitted.

35 Fig. 4 is a detail sectional view through 4—4 of Fig. 1.

Referring to the drawings, 5 is the casing of a search-light provided at its front with converging lens 6.

40 The rear end 7 of the casing is made removable to afford access to the interior. Extending from diametrically opposite sides of the casing are trunnions 8 which are journaled in bearings provided in the bifurcations 9 of a vertical post 10 which is supported by and rotatable in a hollow stand 11 which is secured to a pilot house roof which is indicated by 12.

Secured to the trunnions 8 are forwardly 50 extending arms 13 which are connected to the branches 14 of a forked member 15 which, in turn, is connected to an arm 16 of a tubular controlling rod 17 which extends downwardly through the stand 11 into the pilot house. 18 represents a hand wheel provided on the lower end of the rod 17 whereby the

latter may be rotated by the pilot to correspondingly turn the search-light. Said wheel is also utilized to elevate or lower the rod 17 which, acting through the medium of member 15 and arms 13, serve to regulate the casing axis with respect to a horizontal plane.

The above described devices have been used hitherto and are illustrated to show 65 the application of the invention therewith, although we do not wish to be understood as confining the invention to such an organization.

According to the present invention we 70 provide within the casing a carriage 20 which is movable lengthwise thereof by being slidable upon guide rods 21 extending through apertured lugs 22 and have their ends rigidly connected to blocks 23 which 75 are rigidly secured to the casing 5. As shown, a longitudinally arranged screw 24 is journaled at its ends in the blocks 23 and engages in a nut 24¹ depending from the carriage so that when the screw is turned in one 80 rotary direction or the other the carriage is respectively advanced toward or retracted from the front of the casing.

To effect such rotary movements of the carriage actuating screw we preferably use 85 two cords 25 and 26 wound in reverse directions about the screw and thence extending through the controlling rod 17 into the pilot house as at 25¹ and 26¹.

For convenience of the operator in selectively using said cords the same have desirably attached thereto, different shaped bodies as, for example, a cube 25² and ball 26² to be readily distinguishable in the dark by touch.

95 27 represents an incandescent lamp bulb having circuit wires 28 extending as through the rod 17 to a source of electric energy.

For the purpose of regulating the source of light to be located in the focal axis of the 100 lens the lamp bulb is adjustable vertically as by means of a wedge or cam shaped socket 30 and a flanged ring 31 surrounding the socket extension 30¹ and secured to the carriage.

105 32 represents a reflector disposed to the rear of the source of light and is connected to a standard 33 which, in turn, is connected for horizontal adjustments to a bracket arm 34 arranged for vertical and 110 rotary movements upon a post 35 which is secured to the rear end of the carriage.

The rear end of the casing is removed for regulating the relative positions of the lamp bulb and the reflector.

To effect the coincident movements of the lamp bulb and the reflector toward or from the lens 6 the operator exercises a pull upon the cord ends 25¹ or 26¹ which will suitably rotate the screw 24 to impart the desired movement to the carriage upon which the bulb and reflector are mounted.

When the source of light as represented by the filament A is in approximately the position in which it is illustrated by full lines in Fig. 1, the light rays which are effective with respect to the lens, will be within the angle between the dotted lines a, a and such rays by passing through the lens are delivered in a concentrated beam included between the dotted lines a¹, a¹.

By advancing the carriage toward the lens, however, to position the source of light at B, for example, the effective light rays, with respect to the lens, will be within the angle of the dotted lines b, b and which in passing through the lens are refracted to extend as denoted by b¹, b¹ outside of the referred to concentrated beam with a diverging beam.

What we claim, is—

In a searchlight, the combination with a casing having a lens at the front end thereof, of a stationary stand, a hollow post mounted in said stand and serving as a support for the casing, said post serving as a vertical pivot for the casing, and horizontal pivot connections for the casing carried by said post, of a carriage provided in the casing for longitudinal movements relative thereto, an electric lamp and a reflector mounted on said carriage, devices provided in the casing and operatively connected with said carriage for effecting travel to the latter, means extending through said post for rotatably moving said casing about the axes of both the vertical and horizontal pivot connections therefor, and means extending through said post for actuating said devices to cause the carriage to convey the lamp and reflector toward or from said lens.

Signed at Seattle, Washington, this 11th day of February, 1920.
